UNITED STATES PATENT OFFICE

149,848

DESIGN FOR A TOY GLIDER OR THE LIKE

Henry Struck, Old Lyme, Conn.

Application February 21, 1946, Serial No. 126,818

Term of patent 3½ years

(Cl. D34—15)

To all whom it may concern:

Be it known that I, Henry Struck, residing at Old Lyme, county of New London, State of Connecticut, have invented a new, original, and ornamental Design for a Toy Glider or the like, of which the following is a specification, reference being had to the accompanying drawings, forming part thereof.

Fig. 1 represents a perspective view of a toy glider showing my new design.

Fig. 2 represents a front elevational view thereof.

Fig. 3 represents a side elevational view thereof.

Fig. 4 represents a bottom plan view thereof.

I claim:

The ornamental design for a toy glider or the like, as shown.

HENRY STRUCK.
